NEON TUBE LIGHTED ADVERTISING DISPLAY

Robert L. Lett and Cyril Hedrick, La Crosse, Wis.

Application April 7, 1949, Serial No. 1,860

Term of patent 3½ years

(Cl. D80—9)

To all whom it may concern:

Be it known that we, Cyril Hedrick and Robert L. Lett, respectively citizens of the United States of America, both residing at La Crosse, in the county of La Crosse and State of Wisconsin, have invented a new, original, and ornamental Design for Neon Tube Lighted Advertising Display, of which the following is a specification, reference being had to the accompanying drawing, forming a part thereof.

In the drawing:

Figure 1 is a perspective view of a neon tube lighted advertising display embodying our new design.

Figure 2 is a rear elevational view.

The end of the display opposite to that seen in Figure 1 is identical.

We claim:

The ornamental design for a neon tube lighted advertising display, as shown and described.

ROBERT L. LETT.
CYRIL HEDRICK.
